Filed Oct. 22, 1970, Ser. No. 25,597

Term of patent 14 years

Int. Cl. D16—01

U.S. Cl. D61—1

FIG. 1 is a front elevational view of a single lens reflex camera showing my new design,

FIG. 2 is a rear elevational view thereof.

FIG. 3 is a left side elevational view thereof,

FIG. 4 is a right side elevational view thereof,

FIG. 5 is a top plan view thereof,

FIG. 6 is a bottom plan view thereof, and

FIG. 7 is a front perspective view thereof.

The characteristic feature of my new design resides in the particular appearance and configuration of the waist-level viewfinder atop the camera body, all as shown.

I claim:

The ornamental design for a single lens reflex camera, as shown.
